UNITED STATES PATENT OFFICE

104,776

DESIGN FOR PAPER FOR BOX COVERINGS AND SIMILAR ARTICLES

John N. Hazen, Holyoke, Mass.

Application December 10, 1935, Serial No. 60,002

Term of patent 3½ years

To all whom it may concern:

Be it known that I, John N. Hazen, a citizen of the United States, residing at Holyoke, in the county of Hampden, State of Massachusetts, have invented a new, original, and ornamental Design for Paper for Box Coverings and Similar Articles, of which the following is a specification, reference being had to the accompanying drawing, forming part thereof.

Figure 1 is a plan view of a piece of paper for box coverings, and similar articles, showing my design.

Figure 2 is an enlarged sectional view taken along the line 2—2 of Figure 1.

In my design for paper for box coverings and

similar articles, as shown in the drawing, I employ a background of embossed curved lines. Provided on this background are a plurality of conventional representations of evergreen trees. The trees are composed of embossed parallel lines, the lines composing one-half of each tree being substantially at right angles to the lines composing the adjacent half, resulting in a changeable sheen on the surface of the paper.

I claim:

The ornamental design for paper for box coverings, and similar articles, as shown and described.

JOHN N. HAZEN.
